UNITED STATES PATENT OFFICE.

JOHN A. DAILING, OF QUINCY, ILLINOIS, ASSIGNOR OF ONE-HALF TO ANTHONY BADAMO.

HEAD-BLOCK FOR HAY-BALERS.

1,380,639.

Specification of Letters Patent. Patented June 7, 1921.

Application filed February 13, 1920. Serial No. 358,531.

To all whom it may concern:

Be it known that I, JOHN A. DAILING, a citizen of the United States of America, and a resident of Quincy, in the county of Adams 5 and State of Illinois, have invented certain new and useful Improvements in Head-Blocks for Hay-Balers, of which the following is a specification, containing a full, clear, and exact description, reference being had to 10 the accompanying drawings, forming a part thereof.

This invention relates to improvements in head blocks for hay balers, and has for its primary object a head block for baling 15 presses which is so constructed that in the event of the block becoming jammed and broken, the broken part can be removed and a new one replaced in a short time, avoiding any delays as is the case with the present 20 head blocks, as when one of these becomes broken it is necessary to make an entire new block which will take the greatest part of the day.

In the drawings:

25 Figure 1 is a top plan view of a baling press with the top portion removed, showing one of my blocks in position; Fig. 2 is a face elevation of the same;

30 Fig. 3 a top plan view; Fig. 4 a plan view of the insert block made use of;

Fig. 5 a fragmental edge view of a portion of the head block; and

35 Fig. 6 a perspective view of one of the sectional portions of the block.

In the drawings: 7 indicates a baling press which is of ordinary construction and is provided with a reciprocating plunger 8 and the locking dogs 9, this portion of the device 40 being an old and well known construction will not be described in detail.

Within the space occupied by the plunger is inserted my improved head block 10 which is composed of slats 11 and 12. These slats 45 are connected together in pairs, see Fig. 6, and are separated from each other by means of the blocks 13, these blocks being slightly longer than the width of the slats so as to form slots 14 between the adjacent faces of the slats. The slats have their edges beveled as at 14 so as to form a substantially V-shaped slot between the two adjacent slats. The purpose of these slots is to permit the 50 insertion of the tie wires around the ends of the compressed bale, and the object of the

inclined faces of these slots is to allow the ready removal of the head, which would not be the case with the slots provided with a rectangular enlargement.

When the slats have been secured to the 60 blocks 13, a rectangular opening 15 is formed between the two inner faces of the blocks, and through this is inserted the block 16. This block is of sufficient width to fill in the entire opening 15, and is provided with 65 openings 17 which register with openings 18 formed in the blocks, and through these openings are passed bolts 19 which secure the strips in position on the block.

On one face of the blocks and near its upper edge is attached a strap 20, the purpose of which is to lower the block into position within the press. The upper and lower edges of the block are likewise provided with recesses 21. This permits the strap to 70 fold over the edge of the block and still not project beyond the surface thereof.

It has been found by the use of a block of my construction that in event the head block becomes jammed between the upper edge 80 of the compression chamber and the plunger that the board or block 16 will break but none of the other slats will suffer damage. This damage is prevented by the metallic edges 22 which are U-shaped in form and are secured around the ends of the slats 11 and 12 and the block 13. These metallic edges also contact with the dogs 9 and save the rapid wearing out of the head block.

When this breakage occurs, it is only necessary to insert a new block 16 which can be done in a very short time by merely removing the bolts 19 and then slipping the double slats off of the broken block and on to a new one, and then securing them in place. This 90 takes but a very few minutes, and the only tools necessary are a plane, wrench and auger, whereas in the present construction of head blocks it is necessary to have a rabbeting plane and numerous other tools which 95 are usually not found on a farm, and which require the handling of a skilled mechanic rather than a farm hand.

Having fully described my invention, what I claim is:

1. A head block for baling presses comprising a pair of blocks, slats secured on opposite faces of said blocks so as to form a rectangular space, a block adapted to be inserted in said space, and means for securing 110

the first mentioned blocks and the slats to the second mentioned block.

2. A head block for baling presses comprising a pair of blocks, slats secured on opposite faces of said blocks so as to form a rectangular space, a block adapted to be inserted in said space, means for securing the first mentioned blocks and the slats to the second mentioned block, and a strap secured 10 to one of the slats for lowering the head block into the press.

3. A head block for baling presses com-

prising a central block, a plurality of slats spaced apart and removably secured to opposite faces of the block by means of bolts 15 passing entirely therethrough, a plurality of short blocks adjacent the long edges of the central block, said short blocks being permanently secured to the slats, and metallic U-shaped members secured around the ends of 20 the slats and the short blocks.

In testimony whereof I have signed my name to this specification.

JOHN A. DAILING.
